UNITED STATES PATENT OFFICE.

WILLIAM BAKER, JR., OF BALTIMORE COUNTY, MARYLAND.

DESIGN FOR A BOTTLE.

SPECIFICATION forming part of Design No. 19,125, dated June 4, 1889.

Application filed April 29, 1889. Serial No. 309,116. Term of patent 14 years.

To all whom it may concern:

Be it known that I, WILLIAM BAKER, Jr., of Baltimore county, and State of Maryland, have invented a new and useful Design for a 5 Bottle, of which the following is a complete description.

Figure 1 is a perspective view of the bottle as it appears when finished. Fig. 2 is a cross-section taken on line $x\ x$ of Fig. 1, or on any 10 line parallel with the line $x\ x$ drawn through the body of the bottle. Fig. 3 is a view looking down upon the top.

The shape of the body of the bottle is as follows: Viewing Fig. 2, which shows a cross-section, A is the ordinary flat back generally used upon bottles known as the "Blakes." Upon this flat back is usually blown or otherwise placed the name of the apothecary, grocer, or other party whose goods are put up 15 in these bottles. At the terminals of the line A which makes the back, two concaved lines a and a' project outwardly and inwardly and form part of the back and a portion of the sides of the bottle. From the terminals of 20 these concaved lines the rest of the sides and the entire front of the bottle are formed by the oval line B, which sweeps around and joins the ends of the lines a and a' about in 25 the form shown. Upon this front B is usu-

ally pasted the label containing the description of the contents, or whatever else may be desired to place thereon. This gives a long line and smooth surface for the label and makes a very attractive bottle. The body of the bottle is of the same configuration from 30 the top to the bottom. The shoulder C forms a gentle curve both ways, from side to side and from front to back, and in the center is placed the neck D and mouth-piece, as shown in Figs. 1 and 3.

What I claim, and desire to secure by Letters Patent, is—

A design for a bottle having a body of uniform configuration bounded by a straight line at the back, two concaved lines, as a and a' , 45 extending from the terminals of the back line inwardly and outwardly and forming part of the back and a portion of the sides, the ends of the latter joined by the oval line B, which forms the other portion of the sides and all 50 of the front, the body being surmounted by the curved shoulder C, in the center of which is placed the neck D, substantially as shown and described.

WILLIAM BAKER, JR.
